UNITED STATES PATENT OFFICE.

FRANCIS M. NASH, OF CANAL FULTON, OHIO, ASSIGNOR TO HIMSELF AND
WILLIAM H. STEVENS, OF WINONA, MINNESOTA.

IMPROVEMENT IN HAY AND COTTON PRESSES.

Specification forming part of Letters Patent No. 179,045, dated June 20, 1876; application filed
June 8, 1876.

To all whom it may concern:

Be it known that I, FRANCIS M. NASH, of Canal Fulton, in the county of Stark and State of Ohio, have invented certain new and useful Improvements in Power-Press for Hay, Cotton, Wool, Hops, &c., of which the following is a specification:

Figure 1 represents a perspective view of the press. Fig. 2 represents a longitudinal vertical section of the same. Fig. 3 represents a transverse vertical section through the lower portion of the same. Fig. 4 represents a perspective view of the main operating sprocket cam-wheel, detached from the press. Fig. 5 represents in perspective the double wedge used to release the lifting-pawls from contact with the central rod.

The object of my invention is to furnish, for the use of farmers, cotton-planters, and others, a powerful press, by which hay, cotton, or other material can be rapidly and closely packed. The construction of the press being a simple one, allows the same to be built for less cost than other more complicated presses.

My invention relates to the manner in which the platen is raised up against the material that is to be pressed, by means of a central rod elevated by gripping-pawls operated by a lifter bar or yoke traveling up and down over the edge of a sprocket cam-wheel; also to a retaining-pawl in connection with the central rod; also, to the manner in which the yoke and cam-wheel are provided with friction-rollers to support them, and in the manner in which said cam-wheel is journaled; also, to the manner in which the cam-wheel is operated by a chain and power-wheel through a rotating lever, all as will now be more specifically set forth.

In the drawings, the frame of the press is represented at A. It forms a rectangular box, in which the material to be pressed is introduced from above. The upper part of the press is hinged to the frame A at a, so that it can be readily opened for the removal of the bale that has been pressed. This upper part is formed of the two end pieces B, and two doors, B', made of slats, connected to the end pieces B by hooks b. The top of the press C is also made of slats, for the convenient in-

roduction of the tie-bands around the bale. The slats are united above to longitudinal pieces c, and a central beam, C', that projects over the ends of the press. The top C of the press is provided with bars or strips c', projecting over the end pieces B, to keep them from spreading apart under the pressure exerted within. It is also hinged at a' to one of the doors B', so as to remain in convenient position to close the press. After it is closed it is so retained by two links, d, hinged to the end pieces at d', engaging over the projecting ends of the central beam C'. The platen E of the press is mounted upon the top of a central rod, e, by which it is forced upward by two lifting-pawls, f, that embrace and impinge against the sides of the said rod e. Each of the lifting-pawls f rests upon a vertical projection of different height of the lifter-bar or yoke G. This yoke is provided with friction-rollers h, that travel upon the edge of a rotating sprocket cam-wheel, H, mounted upon a central bearing, I, and supported by friction-rollers i, located in boxes i' upon the lower portions of the frame of the press. The central opening in the yoke G and bearing I are slightly larger than the rod e, so as to allow it to move freely up and down. To keep the yoke from rotating under impulse of the cam-wheel H, it is extended so that its extremities engage in vertical slots of the guides J, the cam-wheel being provided with two inclined planes upon its periphery, one opposite to the other, so that the yoke remains at all times level. While the yoke and lifting-pawls f descend for a new gripe upon the lifting-rod e, it is retained to the height previously reached, by the retaining-pawl K, pivoted to the frame at k. The lifting or cam wheel H is rotated by means of an endless cable-chain, L, passing around it and around a power-wheel, M, pivoted to an adjustable slide, n, mounted upon a horizontal frame, A', the wheel M being in its turn rotated by a sweep or lever, m.

To operate with this press, it is placed over a pit, which permits the descent of the platen-bar, e, which passes through the eye of each lifting-pawl, through the yoke, and through the central bearing of the cam-wheel, and also through the eye of the retaining-pawl. The

platen having been lowered, the press is filled from above, and the top C replaced above it, and secured by the links d. The power-wheel is rotated, and through it and the chain L, the lifting cam-wheel is rotated. The friction-rollers h of the yoke, following the inclined planes of the cam, lift the yoke and the pawls f that impinge against the rod e, lifting the latter until the highest point of the cam is reached, when the retaining-pawl K will hold the rod, while the yoke and lifting-pawls descend for a new lift, and the operation is repeated automatically at each revolution of the cam-wheel, until the platen reaches the point desired. The bale is then bound and secured, the doors opened, and it is removed from the press. The platen is then lowered by inserting the double wedge P between the top of the yoke and the lifting-pawls f, bringing the latter to a horizontal position to release the rod e. Then the operator places his foot on the outer end of the retaining-pawl, tips it, and the lifting-rod and platen descend by their own gravity to a proper position for refilling the press.

In a full-size machine the sprocket power-wheel, the chain, and the lower part of the lifting-cam are covered with planking, under which the chain runs, and is entirely protected from the horses' feet.

Having thus described my invention, what I claim is—

1. In combination with the platen of a press, and its carrying and sustaining rod, the gripping-pawls f, operated by a yoke, G, substantially as and for the purposes described.

2. In combination with the rod e, yoke G, and pawl f, the vertical projections g of unequal height to operate the pawls, one above the other, substantially as described.

3. In combination with the rod e and yoke G, having friction-rollers h, the sprocket-wheel H, having two inclined planes formed upon the edge to lift the yoke, substantially as described.

4. In combination with the cam-wheel H and rod e, the central collar-bearing I, and friction-rollers i, located in the same vertical plane as the rollers h, substantially as set forth.

5. In combination with the cam-wheel H, operating substantially as described, the power-wheel M, and chain L, located in the same horizontal plane as the cam-wheel H, substantially as and for the purposes set forth.

6. In combination with the rod e and lifting-pawls f, operated by the yoke G, the retaining-pawl K, constructed and operating substantially as described.

7. In combination with the yoke G, carrying the lifting-pawls f and the cam-wheel H, the friction-rollers h, traveling upon the edge of said cam, substantially as and for the purposes described.

In testimony that I claim the foregoing as my own, I hereunto affix my signature in presence of two witnesses.

FRANCIS M. NASH.
